UNITED STATES PATENT OFFICE.

CARL MACK, OF NEW YORK, N. Y., ASSIGNOR TO HENRY C. KARLSON, OF HASBROUCK HEIGHTS, NEW JERSEY.

YELETING-MACHINE.

Serial No. 1,300,219.

Specification of Letters Patent.

Patented Apr. 8, 1919.

Application filed June 19, 1916. Serial No. 104,510.

To all whom it may concern:

Be it known that I, CARL MACK, a citizen of the United States, and resident of the borough and county of Queens, in the city and State of New York, have invented certain new and useful Improvements in Eyeleting Machines, of which the following is a specification.

The present invention relates to machines designed to affix eyelets to papers, textile fabrics, dressed leather, or other sheet material, and it appertains more especially to a device of this character wherein the eyelets to be affixed are supplied automatically from a magazine containing the same.

One of the objects of the invention is to produce an improved machine for the purposes set forth, by means of which the eyelets can either be fed singly from the magazine and forced through a certain thickness of paper or the like simultaneously with the piercing thereof, or else applied to a thicker layer of the material previously punched in the machine by a separate operation, the eyelets in the latter case being also supplied automatically and inserted as well as clenched during the second operative step performed by the machine.

A further object is the production of a simple and effective eyeletter, composed of few and durable parts convenient to manipulate, not liable to get out of order, and capable of being manufactured at low cost.

Another object is to provide an eyeleting machine with a magazine devoid of internal stirrers and adapted instead to receive a wobbling motion calculated to prevent arching or clogging of the eyelets therein, and preclude as well their being tossed out while the magazine is bodily agitated.

Other objects and advantages of the invention will become apparent as the specification proceeds.

With the aforesaid objects in view, the invention consists of the improvements, novel construction, arrangements and combinations of parts hereinafter described, defined in the subjoined claims, and illustrated in their preferred embodiments by the annexed drawings, wherein like elements are designated by the same reference characters throughout.

In the said drawings:—

Figure 1 is a rear elevation of a device embodying a convenient form of the invention, especially adapted for fastening paper sheets together;

Fig. 2 is a right hand side elevation of the device disclosed by the preceding view, parts being broken away and other parts shown in section;

Fig. 3 is a top plan view of the same device;

Fig. 4 is a sectional elevation of the device, looking from the front thereof, that is, the side opposite that shown in Fig. 1;

Fig. 5 is an enlarged, fragmentary bottom plan view of an element included in Fig. 2; and

Fig. 6 shows diagrammatically the action of the eyelet setting and feeding mechanisms in several operative positions.

The advantages of the invention are best realized in a structure comprising, as shown, a magazine communicating at a right angle, or approximately so, with an eyelet guide, these elements being mounted at one side of and operated by an eyelet setting plunger, adapted to impart thereto a compound swinging and rocking motion, as hereinafter described.

Referring to the several views aforesaid, the numeral 11 therein denotes a base or foot plate, from which extends an arm 12, carrying a housing 13. These various elements may be hollow, as shown. Holes 14 are provided in the base to receive screws for holding it to a primary support, and a plate 15, covering the upper end of the housing is similarly fastened thereto, as by screws 16.

The said housing 13 is formed with a guide 18, for a plunger 19 and with bearings 20^a, 20^b, for a spindle 21. An operative connection is effected between the plunger and the spindle, the same being shown in the present exemplification of the invention as consisting of a rack 22, carried by the said plunger and engaged by a pinion 23, fixed to the said spindle. To the outer end of the latter is secured a crank arm 24, carrying at its free extremity a stud 25, on which is mounted a knob 26, for convenience in manipulation. Although this

construction is here represented as the preferred one, it should nevertheless be understood that any other suitable combination or arrangement of parts may be employed instead.

As seen in the lower portion of Fig. 2, the plunger 19 is provided with an axial bore 28, constituting a barrel for a helical spring 29, designed to oppose the upward movement of a shouldered impaling pin 30. The latter is slidably guided in the lower end of the plunger, and the barrel containing the spring is closed at the top by means of a screw plug 31. Below the pin 30, and disposed in direct alinement therewith, is a piercing stud 34, extending upwardly from an anvil plug 35, set in the base 11, centrally beneath the said plunger.

The last mentioned elements may be used alone to punch or pierce a layer of paper, fabric, or like material placed upon or over the stud 34. As will be noticed by reference to Fig. 4, this stud is slightly dished on top, as at 36, presenting at that point a sharp cutting edge which readily pierces or punches a hole through the material operated upon, when the plunger is forced down against the same. The hole having been formed, the plunger is next withdrawn so as to enable the impaling pin 30 to receive an eyelet, as E, which will be forced to enter the previously punched hole in the material when the plunger is caused to descend again and the impaling pin again registers with the stud 34. Further downward travel of the plunger operates to press the lower sharp edge of the eyelet against an annularly recessed or grooved part 37 of the anvil 35, that surrounds the central piercing stud 34, thereby causing the said lower edge to roll over and flatten out, producing in effect a flange corresponding to the head of the eyelet and forming therewith a pair of parallel retainers between which the layers of material are securely fastened together.

The mode of procedure just outlined conforms in substance with the practice generally followed in this art.

A gage 40 is provided, to assist in correctly locating the material to be eyeleted with relation to the punch, for instance, in squaring sheets of paper that are to be bound together and insuring that the eyelets be inserted uniformly in parallelism with one edge thereof at any specified distance previously determined. This gage is carried by a rod 41, which may be adjustably held in position by means of a screw 42, in the lower part of the arm 12.

Suspended at one side of and offset from the plunger 19, is a guide or chute 50, for the eyelets E. This guide includes shallow grooves 51, located internally on opposite sides thereof in position to receive the flange 55 of each eyelet as it slides between them, and

a central channel 52, of greater depth and just sufficient width to provide a clearance for the tubular eyelet shank or body. The two grooves and the channel are covered by a removable plate 53 held by screws 54 to the sides of the chute.

An arm 55 extends inwardly from one side of the said chute, below the center of gravity thereof, toward the housing 13, and is provided at its inner end with a hub 56 having a hole 57 through which is passed a screw 58, received at its opposite ends in ears 59^a, 59^b, projecting outwardly from the rear of the housing. The screw 58 thus affords a pivotal means of suspension for the arm 55 and the chute 50 connected therewith. Moreover, the ends of the hub 56 are rounded, as shown in Fig. 1, and the hole therein is made of somewhat larger diameter than the screw 58, as seen in Fig. 2, to allow the arm 55 a certain amount of lateral play between the ears 59^a, 59^b, with the result that the chute is permitted considerable freedom of movement, especially the upper end thereof, which not only is enabled to swing in a vertical plane, but also has a wobbling or rocking motion sidewise. These combined swinging and rocking movements are particularly advantageous in insuring the proper descent of the eyelets, which are deposited in a magazine 60, attached to and communicating with the upper end of the chute, preferably at a right angle, as shown. The action is such as to preclude the bridging or building up of the eyelets within the magazine.

Referring further to the arm 55, it will be noted that the same is provided at its upper edge with a rearwardly pointed spur 64, adopted to be engaged by a detent, which as shown may be in the nature of a latch 65, pivotally suspended from a screw or pin 66, passed through upper extensions, of the ears 59^a, 59^b, above the hub 56 of the said arm. When the eyelet chute 50 is swung upward to bring the spur 64 on the arm 55 thereof into engagement with this latch 65, it is held in an inoperative position, as indicated in Fig. 1. The chute can likewise be rendered inoperative and maintained in a raised position, independently of any latch or detent, simply by causing the upper end thereof to lean over and rest against the corresponding end of the housing 13, as will be readily understood, the arm 55 being sufficiently long and free to move about the pivot 58 to admit of this arrangement.

On the underside of the said hub 56 of the arm 55 is provided a stop 67 which projects downwardly in a direction opposite from the before mentioned spur 64, and has a working fit between lower extensions of the ears 59^a, 59^b, providing a shallower recess at that point than where the hub 56 is located. While the stop 67 is in engage-

ment with these ears, it guides the arm 55 and chute 50 in such a way that they can only swing in a single direction, but as soon as the stop has been withdrawn the arm and the chute are again free to receive the compound oscillatory and rocking movement referred to hereinbefore.

The swinging motion imparted to the eyelet chute is derived directly from the plunger 19, without any intermediate connections. To this end the lower extremity of the cover plate 53 for the chute is curved forwardly and extended out as at 68, in order that it may reach beyond the front side of the plunger, as indicated in Fig. 2, when the arm 55 is unlatched and the chute 50 tilts rearward by its own weight, until arrested by the stop 67 meeting the rear wall of the housing 13, between the ears 59^a, 59^b. The lower end 20 of the said cover plate is formed with an oblique slot 69, Figs. 1, 2 and 5 to afford a clearance for the impaling pin 30, when the curved portion of the plate underlies the plunger. Then the lower rounded extremity 25 of the latter is in position to be driven against the correspondingly curved part 68, which it encounters upon the turning of the crank 24 in the required direction thereby causing the magazine end of the eyelet chute 30 to swing up toward the housing, until the lower end of the chute has been cleared by the plunger during its downstroke. As the stop 67 guides the chute while the slotted lower portion thereof traverses the path of 35 the plunger, no side strain worth speaking of is exerted on the pin 30.

The before described grooves 51 and channel 52 constitute a raceway for the eyelets inside the chute 50. The lower terminal of 40 this raceway is curved in conformity with the cover plate 53, so that the eyelets E sliding down by gravity under the same will come one after another into the path of the plunger 19, with the outer and lowermost 45 eyelet directly beneath the impaling pin 30. Consequently when the plunger descends, as indicated in Fig. 2, the pin passes through this eyelet and operates to segregate and pull it away from the other ones, as the 50 rounded end of the plunger is being forced past the outer edge of the curved part 68 of the chute.

In order to prevent the eyelets that remain in the chute from sliding out prematurely therefrom, a retainer is provided, which may conveniently be in the shape of a lever 70, having an upturned portion 71. This lever is shown as pivoted on the shank of a screw 72, entered into the underside of a 55 heel-portion 73, formed at the lower part of the chute. A torsion spring 74 holds the lever 70 up against a stop 75, projecting downwardly from the heel 73, Figs. 1 and 5, so that the upturned portion 71 of the lever 60 blocks the way of the eyelets. To accom-

modate the impaling pin 30 the retaining lever 70 is notched at 76, and has the inner face of its upturned portion beveled, as indicated at 77, so that when the pin drags thereon, incidentally to pulling or forcing 70 out the eyelets, the beveled portion will slide off the said pin and thereby cause the lever to swing to one side, permitting a previously impaled eyelet to be withdrawn. Immediately thereafter, the retaining lever snaps 75 back into its normal position in rear of the impaling pin, and thus holds the line or column of eyelets that advances toward it from going any farther. The said spring 74 is contained within a recess 78, formed in the 80 heel portion 73 of the chute 50.

The hereinbefore mentioned magazine 60 comprises a receptacle of substantially pyriform outline, as viewed in plan, one side thereof drawn to a taper and fastened to a backing piece 82. The latter constitutes an attachment to the chute 50, to which it is held from the rear by screws 83. Preferably, this backing piece is composed of three co-acting elements, now to be described in 85 succession: First, an apertured plate 84 is made to extend transversely across the interior of the magazine, presenting therein a plurality of openings 85, the lower portions whereof are widened as at 86, Fig. 4, to accommodate the heads of the eyelets, when the latter are lying with their tubular shank portions uppermost on the bottom 87 of the receptacle. Secondly, a guide plate 88 is set above the bottom 87, at a sufficient distance therefrom in rear of the apertured plate aforesaid to provide a clear space for the eyelets to slide under the guide, without permitting them, however, to tip or turn over on their sides and become stuck 90 between the opposed surfaces 87 and 88. A passage 89 is formed between the latter-named surfaces with its sides converging in conformity with the tapering rear portion of the magazine and terminating in an 95 aperture 90, which leads out of the backing 81 at a substantially right angle into the raceway of the chute 50. The aperture 90 permits only a single eyelet to pass therethrough at any one time. Owing to the 100 recurrent swinging motion imparted to the magazine and chute, the eyelet receives a sufficient impetus therefrom to cause it to slide to the rearmost edge of the passage 89 and there make a quick quarter turn so as 105 to drop from the magazine into the chute, where the head of the eyelets becomes at once engaged by the lateral grooves 51, the shank following the central channel 52. Thirdly, an inclined partition 91 is provided in the 110 magazine, the same extending from the top of the backing piece 82 down to the upper edge of the apertured plate 84. The office of this inclined partition is to utilize the 115 force of agitation to which the eyelets are 120

subjected through the compound movement imparted to the chute and magazine, as they slide up and down the partition 91 with less friction than would result from their being allowed to roll over one another for the full length of the floor 87. The building up and interlocking of the eyelets is obviated thereby.

A further advantage, resulting from the vibratory wabbling motion of the magazine, is that wherever a mass of eyelets slides down the inclined plate 91 they push or sweep away from the apertured plate 84 such other eyelets as may have already gathered or become packed in immediate proximity of the latter, and thus break up any tendency thereof to bridge or arch in front of the exit apertures. Those eyelets which have passed through the openings 85, in the plate 84, are prevented for the most part from sliding again therethrough, as the wabbling or rocking motion brings them opposite the solid portions of the said plate, and the next downward oscillation of the magazine causes the eyelets then in the passage 89 to push one another in a rearward direction until the innermost one of them topples over into the chute, into which they drop in succession, through the opening 90.

For the purpose of enabling the operator of the device to detect and dislodge imperfect eyelets, if the like are perchance deposited in the magazine and happen to be come stuck in the chute or in the interconnecting aperture 90, two or more slots, as 92 and 93, are formed both in the front and rear walls of the chute, for instance, opposite the said aperture, and at some point in the cover plate 53, adjacent to the arm 55, Figs. 1 and 2.

The magazine 60 is provided on top with a hinged lid 94, adapted to be snapped over a suitable fastening button, as 95. The lid, it is understood, prevents the eyelets from being spilled out while the magazine is agitated.

The action of the plunger 19 and of its impaling pin 30 upon the delivery end of the chute 50 is clearly illustrated in Fig. 6, which shows these elements in varying positions, respectively indicated by the letters A, B, C, and D. As represented at A, the plunger 19 upon being driven down against the lower end of the chute causes it to recede therefrom, and at the same time the pin 30 sliding out of the oblique slot 69 imparts a lateral movement to the chute, which produces the wabbling hereinbefore set forth, due to the peculiar pivotal connection with the plunger housing, that is, the means of suspension. As soon as the pin 30 has come out of the slot 69, and the plunger descends farther past the end of the chute 50, then the latter shifts to the position indicated at B, which

position it retains until the setting of the eyelet is effected. Next, the plunger is withdrawn together with the impaling pin and the delivery end of the chute bears against both of them in turn, till the point of the pin 30 clears the chute, when the delivery end thereof slides under it, along the path denoted by the dotted line "c" at "C." Finally, when the lower end of the chute has advanced under the plunger far enough for the impaling pin to enter the inner end of the slot 69 as represented at D, the several elements namely, the pin, the plunger, and the chute have regained their respective original positions, as they appear in Fig. 2, although this figure shows the pin 30 as projecting below the plane of the raceway for the eyelets, it is understood that the plunger 19 is elevated sufficiently high for the said pin to engage these eyelets consecutively.

While certain preferred embodiments of this device have been shown and described, it will be understood that changes in the form, arrangements, sizes, proportions and details thereof may be made, without departing from the scope of the invention as defined by the appended claims.

Having described my invention what I desire to secure by Letters Patent and claim is:

1. An eyeleting machine including, in combination, an affixing device, means for feeding eyelets thereto, and a suspension for said feeding means enabling it to receive an oscillatory wabbling motion.
2. An eyeleting machine including, in combination, an affixing device having an impaling member and a feeding mechanism for the eyelets actuated by direct contact with the impaling end of said device.
3. An eyeleting machine including, in combination, an affixing device having a vertically operable impaling member and a gravitating eyelet feeder set in motion directly through impact by the end of the latter.
4. An eyeleting machine including, in combination, an affixing device, a feeder therefor, and means suspending the latter loosely and eccentrically whereby it is adapted to receive a compound swinging and rocking movement.
5. An eyeleting machine including, in combination, an affixing device, a feeding mechanism therefor, a support, and a single pivotal means suspending said mechanism at one side thereof from said support below its center of gravity.
6. An eyeleting machine including, in combination, an affixing device, and an overbalanced feeder having a single pivotal support thereon offset from the line of discharge, the pivot for said feeder being adjacent to its discharge end.
7. An eyeleting machine including, in

combination, an affixing device, a container for the eyelets, and a moving chute operable to deliver the eyelets from said container to said device by direct impact from the end 5 of the latter.

8. An eyeleting machine including, in combination, an affixing device, an eyelet container, and an eccentrically suspended chute constructed and arranged to convey the eyelets from said container to said device by a compound vibratory movement about its means of suspension.

9. An eyeleting machine including, in combination, an affixing device provided 15 with an impaling member, a feeder directly operable by the impaling end thereof, and a container arranged to discharge eyelets into said feeder directly through actuation of the latter by said device.

10. An eyeleting machine including, in combination, an affixing device, a plunger forming part thereof and provided with an impaling member, and a wabbling eyelet chute positioned for oscillation by direct 25 contact with the impaling end of said plunger.

11. An eyeleting machine including, in combination, an eyelet setting plunger having an impaling member, a wabbling chute arranged to convey eyelets thereto, and means for suspending said chute for oscillation by direct contact with the impaling end of said plunger in one direction and by 30 gravity in the opposite direction.

12. An eyeleting machine including, in combination, an eyelet setting plunger, an eyelet chute having its delivery end positioned to be moved by contact therewith, a support permitting oscillation of said chute 40 simultaneously in two directions, and a stop for the latter serving to locate it with relation to the plunger concomitantly with the oscillation.

13. An eyeleting machine including, in combination, an eyelet setting plunger, an impaling element associated therewith, an eyelet chute adapted for engagement at its delivery end by said plunger together with said element, and a means of suspension for 50 said chute causing it to receive a vibratory wabbling movement through contact with either the element or the plunger.

14. An eyeleting machine including, in combination, an affixing device, an oscillatory chute adapted to deliver eyelets thereto, a container for the eyelets carried by said chute, and means within said container and stationary with respect thereto, serving to utilize the agitation of the eyelets to preclude their interlocking.

15. An eyeleting machine including, in combination, an affixing device, a vibratory magazine having a raceway adapted to convey eyelets to said device consecutively one 65 after another, a guide leading from the

body of the magazine into the raceway, and means operating to prevent accumulation of said eyelets prior to their reaching said guide, by permitting part thereof to sweep away another part from the entrance to the 70 guide, said means comprising an apertured barrier and a partition disposed obliquely thereto and to the bottom of said magazine.

16. An eyeleting machine including, in combination, an affixing device, a magazine 75 for the eyelets, a chute arranged to deliver the eyelets to said device from said magazine, a barrier within the latter having alternate openings and solid portions controlling the flow of eyelets into said chute, and means 80 operating to impart a vibratory wabbling movement to the chute and magazine.

17. An eyeleting machine including, in combination, an affixing device, a vibratory magazine having a raceway designed to convey eyelets to said device in single file, a barrier across said magazine formed with plural apertures leading to said raceway, and means within the magazine and stationary with respect thereto and disposed 90 obliquely to said barrier operating to prevent arching of the eyelets in front of the latter.

18. An eyeleting machine, including, in combination, an affixing device having an 95 impaling member, an eyelet chute, means suspending said chute with its delivery end in proximity to said device so as to be oscillated by the impalling end thereof, and other means for holding the chute temporarily 100 out of the plane of actuation.

19. An eyeleting machine comprising, in combination, an affixing device including an eyelet setting plunger and an impaling pin, an eyelet chute pivoted so as to have a wabbling movement with relation to the last named elements, said chute being oscillated by contacting alternately with said pin and said plunger, and a retainer for the eyelets in the lower end of the chute, the arrangement being such that, first, the impaling pin retracts an eyelet held by said retainer and, secondly, the plunger swings the chute 110 out of the way.

20. An eyeleting machine including, in 115 combination, an eyelet setting plunger, an impaling element associated therewith, a chute for the eyelets having its delivery end in the path of said plunger and element so as to be moved thereby, suspending means 120 enabling said chute to receive a vibratory wabbling motion caused by contact with either the plunger or the impaling element, and an eyelet retainer operated by the withdrawal of the latter from said end of the 125 chute.

21. An eyeleting machine including, in combination, an affixing device provided with an impaler, an eyelet chute suspended so as to have a wabbling motion relatively 130

to said device, the lower end of said chute having an oblique slot in engagement with said impaler at the beginning of the working stroke thereof, and means for actuating 5 the device to cause disengagement of the impaler from said slot when extracting an eyelet from the chute while the latter is simultaneously oscillated to effect the descent of other eyelets therein, the retraction of the

device permitting the slotted end of the eye- 10 let chute to swing back to its first position.

Signed at the borough of Manhattan in the county of New York and State of New York, this 25th day of May, A. D. 1916.
